(57) **CLAIM**

I claim the ornamental design for the light transmitting panel, as shown and described.

DESCRIPTION

FIG. 1 is a plan view of the first embodiment of the light transmitting panel;

FIG. 2 is a close-up plan view of FIG. 1;

FIG. 3 is a cross-sectional view taken along Lines 3—3 in FIG. 2;

FIG. 4 is a cross-sectional view taken along Lines 4—4 in FIG. 2;

FIG. 5 is a plan view of the second embodiment of the light transmitting panel;

FIG. 6 is a cross-sectional view taken along Lines 6—6 in FIG. 5; and,

FIG. 7 is a cross-sectional view taken along Lines 7—7 in FIG. 5.

The front and back surfaces of the light transmitting panel are flat.
